UNITED STATES PATENT OFFICE

GEORGES H. BOUGON, OF REDWOOD CITY, CALIFORNIA

DESIGN FOR A RADIATOR ORNAMENT

Application filed April 8, 1929. Serial No. 30,794. Term of patent 3½ years.

To all whom it may concern:

Be it known that I, GEORGES H. BOUGON, a citizen of France, residing at Redwood City, county of San Mateo, State of California, have invented a new, original, and ornamental Design for a Radiator Ornament, of which the following is a specification, reference being had to the accompanying drawing, forming part thereof.

Fig. 1 is a side elevation of a radiator ornament, showing my new design;

Fig. 2 is a front elevation on a reduced scale, with the attaching element shown in Fig. 1 omitted therefrom.

I claim:

The ornamental design for a radiator ornament, substantially as shown and described.

GEORGES H. BOUGON.
